UNITED STATES PATENT OFFICE

121,480

DESIGN FOR A SHOE

Roy Maling, West Roxbury, Mass.

Application November 13, 1939, Serial No. 88,232

Term of patent 14 years

To whom it may concern:

Be it known that I, Roy Maling, a citizen of the United States, residing at West Roxbury, in the county of Suffolk and State of Massachusetts, have invented a new, original, and ornamental Design for a Shoe, of which the following is a specification, reference being had to the accompanying drawing, forming part thereof.

In the drawing:

Figure 1 is a side elevation of a shoe showing my new design. The design is substantially the same on both sides of the shoe; and

Figure 2 is a bottom plan outline of the sole and heel only of Figure 1.

The essential feature of the invention resides in the combination of a wedge-shaped heel portion and an oval-shaped heel portion on opposite sides of a platform element, at the heel region of a shoe, with prominent approximately parallel horizontal grooves in the composite heel, producing a laminated effect.

I claim:

The ornamental design for a shoe, as shown and described.

ROY MALING.
